Attorney

UNITED STATES PATENT OFFICE.

ISAAC L. HENDRICKS, OF CHATTANOOGA, TENNESSEE.

SAFETY RAZOR.

Application filed March 24, 1923. Serial No. 627,443.

To all whom it may concern:

Be it known that I, ISAAC L. HENDRICKS, a citizen of the United States, residing at Chattanooga, in the county of Hamilton and State of Tennessee, have invented certain new and useful Improvements in Safety Razors, of which the following is a specification, reference being had to the accompanying drawings.

10 This invention relates to safety razors and more particularly to that type of safety razor in which the razor embodies means for guiding the strop, by means of which the blade of the razor is stropped and for oscillating the blade to bring alternate faces thereof into engagement with the strop.

An important object of the invention is to provide a device of this character so constructed and arranged that the use of 20 a comparatively heavy blade is rendered possible. As it is well-known to those familiar with this type of razor, in the majority of instances and in fact in all instances with which I am familiar, the guide or cover plate which when the razor is in use abuts the upper surface of the razor is snapped into position and during its final movement engages against the blade. Since these cover plates are spring held in position and final movement into engagement with the blade is made with great rapidity were a heavy blade employed the blow of 30 the cover plate against the blade would have a tendency to snap the brittle material from which heavy blades are formed, thus necessitating the use of a comparatively light, thin and flexible blade which must be often replaced.

Accordingly, an important object of the 40 invention is to provide a cover plate which while firmly engaging the blade does not snap against the blade and accordingly will not shatter the same.

A further object of the invention is to 45 provide an improved holding means for the cover plate which is retained in locking position through engagement with one of the guiding rollers for the strop.

These and other objects I attain by the 50 construction shown in the accompanying drawings, wherein for the purpose of illustration is shown a preferred embodiment of my invention and wherein:—

Figure 1 is a perspective view showing

a safety razor constructed in accordance with my invention;

Figure 2 is a side elevation thereof;

Figure 3 is a vertical sectional view through the cover, being shown in open position in dotted lines; and

Figure 4 is a rear elevation thereof.

Referring now more particularly to the drawings, the numeral 10 indicates a base plate of a razor head, the forward portion of which inclines downwardly as indicated at 11 and is provided at its forward edge with the usual guard teeth 12, which may be of any preferred construction. The base plate is provided at its end edges with upstanding flanges 13, each flange having the rear end thereof projecting slightly beyond the rear end of the base plate 10. Between the flanges 13 is rotatably supported a pair of transversely extending rollers 14 upon which the under surface of a strop 15 is adapted to rest. A third roller 16 is likewise rotatably mounted between the flanges and is adapted to abut the upper surface of the strop for purposes presently to appear. Above the roller 16 pivotal supports are provided for the blade 17, which has a relatively thickened butt portion 18, bearing pivots which extend through the walls. One of these pivots is provided with a small pinion 19, which is engaged by a similar pinion 20 secured to the outer adjacent end of the roller 16, so that upon oscillation of the roller 16 the blade 17 is oscillated to bring one or the other of the faces thereof into engagement with the strop, this construction being one employed in a number of razors.

To the end teeth of the teeth 12 I secure pivots 21, which engage in openings 22 from the ends of arms 23, extending forwardly from a guard plate 24, the forward edge of which is so constructed that when the guard plate is seated it abuts the blade 17 adjacent the forward or cutting edge 25 thereof and forces the same into engagement with the inclined portion and into close proximity with the teeth 12. The free end of this blade is provided centrally with a spring extension 26, adapted to extend over the blade and having at its extremity a nose piece 26, which during the pivotal movement of the blade to closed position engages against the rearmost roll-

er 14. By engaging the rear edge of the plate 24 with the hand the cover plate may be forced downwardly, the nose piece 26 operating upon the roller and accordingly being substantially free from friction. Adjacent this nose piece the extension 25 is bent to form a forwardly directed shoulder 27, which when the cover 24 is fully seated engages the roller to prevent return of the 10 cover to the open position.

Attention is directed to the fact that when the cover is in the open position the same is so positioned that it cannot possibly interfere with proper operation of the blade and 15 to the fact that at this time the extension 25, which is at substantial right angles to the body of the plate 24, is served with a finger rest with a hand holding the handle of the razor and as a means for drawing the 20 razor head downwardly to insure proper movement of the strop with the roller 16.

It will be obvious that the construction and arrangement herein set forth is capable of some change in modification without departing from the spirit of my invention and I accordingly do not limit myself to such specific structure, except as hereinafter claimed.

1 claim:—

20 1. In combination with a razor head having spaced flanges forming a blade support, and having extending therebetween rollers for guiding a strop for use in stropping the blade while in position upon the head, a 25 cover plate covering said blade when in shaving position, pivotally connected to the head and having a resilient extension having a nose piece engaging one of said rollers during the closing movement of the guard 30 plate, and adjacent the nose piece with a

shoulder engaging the roller when in closed position to lock the cover against the turn movement.

2. In combination with a razor head having spaced flanges forming a blade support, 45 and having extending therebetween rollers for guiding a strop for use in stropping the blade while in position upon the head, a cover plate covering said blade when in shaving position, pivotally connected to the 50 head and having a resilient extension having a nose piece engaging one of said rollers during the closing movement of the guard plate, and adjacent the nose piece a shoulder 55 engaging the roller when in closed position to lock the cover against the turn movement, said extension being at substantially right angles to the said guard plate and forming a rest for the finger during stropping of the blade when the guard plate is in the open 60 position.

3. In a safety razor, a head provided at one edge with teeth and at its sides with upstanding flanges, a blade pivoted intermediate said flanges and swingable to engagement with the teeth, strop guiding rollers having their ends mounted on said flanges and extending transversely of the head, a guard plate pivoted to the endmost teeth of said head and swingable to cover 70 the blade when engaged with said teeth, the free edge of said guard plate being provided with a resilient extension engaging and locking upon one of said strop guiding rollers when the guard plate is in the closed 75 position.

In testimony whereof I hereunto affix my signature.

ISAAC L. HENDRICKS.
